UNITED STATES PATENT OFFICE.

CASSIUS M. WALKER, OF PUEBLO, COLORADO, ASSIGNOR TO THE MILLER ELECTRIC SWITCH COMPANY, A CORPORATION OF COLORADO.

SUPPORTING-FRAME FOR ELECTRIC SWITCHES.

1,247,042.

Specification of Letters Patent. Patented Nov. 20, 1917.

Application filed February 26, 1912. Serial No. 679,918.

To all whom it may concern:

Be it known that I, CASSIUS M. WALKER, a citizen of the United States, residing at Pueblo, Colorado, have invented certain new and useful Improvements in Supporting-Frames for Electric Switches, of which the following is a specification.

My invention relates to a supporting frame for electro-mechanical switches and is adapted to contain and retain the several parts thereof in position to be included within a containing box; and the objects of my invention are to provide a means for assembling the underground parts of an electromechanical switch and to permit the whole of the mechanism to be assembled and sustained by the frame work to be placed within an underground box.

I attain these objects by the mechanisms illustrated in the accompanying drawings, in which,—

Figure 1 is a top plan view showing my device included within a box and connections to operating parts; Fig. 2 is a partial longitudinal central section and partial side elevation of my device after the insertion of the well 17 in its retaining socket but prior to the mounting of the operating shaft; Fig. 3 is an end view, at line *a*—*b* of Fig. 4 of the solenoidal section; and Fig. 4 is a perspective view.

This device is applicable to those electro-mechanical switching devices that are enclosed within a box sunk beneath the ground and it is desired to furnish the means of placing and replacing such switching devices without being compelled to remove the whole box, as well as to permit the assembling of the connecting parts; and the ready means of removing the same for repair.

Similar numerals refer to similar parts throughout the several drawings.

Preferably the device is constructed in two parts although it may be constructed of one part without departing from the principle of my invention. The solenoidal frame 2 is composed of the skeleton frame work at ends and sides with angle construction and the

part 4 being the end adjoining the other portion may be provided with a solid end, 50 or a sufficient portion of it solid to form attachment with the adjoining sections. However, the two parts may be cast in one part and simply a web at the end 4 would provide the means of the various attachments desired. The part 3 adapted to contain the mechanical portion of the device is composed of exterior frame uprights with the sustaining piece 18 cast integral with the sides, one end of which is adapted to fit 55 over the plunger 14, and in this part is a circular space 8 adapted to receive the operating shaft. Above this and integral with the sides of the part 3 is the well sustaining bracket 6 with the circular space 7 therein 60 adapted to receive the operating shaft 17. Attached to the core of the solenoid 11 at each end is the insulating material 12 adapted to fit within the interior of the angle end and side pieces of solenoid frame 2, so as to 65 leave the solenoid free from engagement with any of the parts. The two parts 2 and 3 are united by bolt means 6^a through the ends 4 and 5. Below the plunger 14 is a sustaining 70 guide piece 9 which guides the plunger. Attached to the end 5 under the mechanical part is a controlling cam piece 16, V shaped, which sustains and assists to sustain the mechanism and the throwing arm 15. The frame portion 3 is constructed so as to be 75 approximately one half the depth of the frame piece 4 and level with the top of frame 2. The electric connections are made through the lead wires by attachment to the binding posts 13.

It will thus be seen that this device arranges for the holding and binding of all of the parts of an electromechanical switch within a frame work, and the frame work is of such size and construction that it may 80 be dropped into the containing box 1.

I claim:

In a supporting frame for electromechanical switches, the combination with a containing box of a skeleton frame with end and 85 edge pieces constructed with interior angles

and adapted to receive and hold insulating sections attached to a solenoid, a frame comprising a guide for the plunger of a solenoid, a supporting bracket adapted to accommodate the operation of a shaft therein, and a superimposed bracket adapted to form the mounting for an operating shaft, the

said skeleton frame being adapted to fit the interior of said containing box.

Witness my signature.

CASSIUS M. WALKER.
